United States Patent Office.

JONES HARDING, OF DETROIT, MICHIGAN.

Letters Patent No. 95,223, dated September 28, 1869.

IMPROVED BEDSTEAD.

The Schedule referred to in these Letters Patent and making part of the same.

To whom it may concern:

Be it known that I, JONES HARDING, of Detroit, in the county of Wayne, and State of Michigan, have invented a new and useful Improvement in Bedstead; and I do declare that the following is a true and accurate description thereof, reference being had to the accompanying drawings, and to the letters of reference marked thereon, and being a part of this specification.

The nature of this invention relates to the construction of a bed and bed-bottom, in such a manner that it can easily be taken apart and packed for shipment. All of its parts being of wire, it forms an easy couch, and precludes the intrusion of vermin.

A, in the drawings, represents a wire of proper size and length, bent into a rectangular form, with its ends joined together to form the bed-frame, its longer sides being provided with an inner longitudinal rod, B.

A central longitudinal rod, C, is also rigidly secured to the shorter sides of the frame.

The frame so constructed is sustained by a series of supports, D, bent in the form shown in the drawings; and hinged at the crown of their arches to the side-rods B and central rod C, and maintained in a vertical position by the diagonal hook-braces G, pivoted on the longitudinal bars B and C, and which, when necessary, may be unhooked from the supports, and allow them to be folded up against the bed-bottom.

The frame is braced and prevented from twisting by diagonal rods E, passing from the ends to the sides, and rigidly secured to all the longitudinal rods of the frame.

The ends of these diagonal rods are bent upward, to form the hooks F, which engage with and secure the side-rails of the bed in position.

A series of wire springs, H, partially coiled in their central parts, extends diagonally across the bed-frame, from corner to corner and centre to centre thereof, at which points they are secured to the same, and form a portion of the foundation of the bed-bottom, which

is completed by a number of similar springs I, moving transversely on the longitudinal rods B and C. These transverse springs are so made movable, that they may be placed where the superimposed weight is the greatest, to prevent sagging at that particular point.

The head and foot-boards J J', and side-rails L L', are formed into any required shape, and composed of wires woven into any plain or fancy design, with the ends of their horizontal wires bent into loops.

The superstructure being placed on the bed-frame, with the lower rods of the side-rails L L' engaging with the hooks F on the frame, the whole is firmly secured thereto by rods passing down through the loops at the ends of the side-rails and head and foot-boards into the sockets made for that purpose in the corners of the frame A.

If desired, each pair of these rods may be made in one piece, to form an arched frame M M' for supporting a mosquito-bar, as shown in the drawings.

The central longitudinal rod C is placed in the bed for the purpose of preventing the same from sagging on one side when the bed is occupied by a light and a heavy person.

What I claim as my invention, and desire to secure by Letters Patent, is—

1. The frame A, when provided with the longitudinal rods B and C, and diagonal rods E, the supports D, and hook-braces G, arranged and operating substantially as described, and for the purposes specified.

2. The combination and arrangement of the frame A, longitudinal rods B and C, supports D, diagonal rods E, hooks F, diagonal hook-braces G, spring-supports H and I, head and foot-boards J J', side-rails L L', and arch-rods M M', when constructed and operating substantially as herein described, and for the purposes specified.

JONES HARDING.
